UNITED STATES PATENT OFFICE.

GEORGE W. DUNHAM, OF MUSCATINE, IOWA.

DESIGN FOR A SHOE-LACE AND SHOE-TONGUE HOLDER.

45,862.

Specification for Design.

Patented June 2, 1914.

Application filed March 16, 1914. Serial No. 825,180. Term of patent 7 years.

To all whom it may concern:

Be it known that I, GEORGE W. DUNHAM, a citizen of the United States, residing at Muscatine, in the county of Muscatine and State of Iowa, have invented a new, original, and ornamental Design for Shoe-Lace and Shoe-Tongue Holders, of which the following is a specification, reference being had to the accompanying drawing, forming a part thereof.

In the drawing: the figure is a detail perspective view of the shoe lace and shoe tongue holder.

I claim:

The ornamental design for a shoe lace and shoe tongue holder, as shown.

GEORGE W. DUNHAM.
